UNITED STATES PATENT OFFICE

2,375,372

COLTER

Arthur Laitinen, Kimball, Minn.

Application May 6, 1944, Serial No. 534,433

2 Claims.

(Cl. 97—209)

This invention relates to a colter device.

An object of the invention is the construction of a simple and very efficient colter device which will prevent the plow from lifting out of the ground by eliminating the gathering of corn stalks or weeds of any kind in front of the colter device.

Another object of the invention is the construction of a very efficient and novel frame, mounted in a novel and efficient manner upon the standard of the device, which standard is adapted to be attached to the common plow beam of a plow.

A still further object of the invention is the construction of a novel and efficient colter device in which the frame will efficiently slide or pass over, as a runner, foreign matter, such as stalks and the like, and which frame will also have a slight pivotal or turning movement upon its supporting standard, whereby the life of the device is increased by eliminating the possibility of the frame being broken off the standard.

With the foregoing and other objects in view, my invention comprises certain novel constructions, combinations, and arrangements of parts as will be hereinafter fully described, illustrated in the accompanying drawing, and more particularly pointed out in the appended claims.

In the drawing:

Figure 1 is a view in side elevation of a device constructed in accordance with the present invention.

Figure 2 is a view taken on line 2—2, Figure 1, and looking in the direction of the arrows.

Figure 3 is a fragmentary vertical longitudinal sectional view of the device, taken on line 3—3, Figure 2.

Figure 4 is a sectional view taken on line 4—4, Figure 3, and looking in the direction of the arrows.

Figure 5 is an enlarged sectional view taken on line 5—5, Figure 3, and looking in the direction of the arrows.

Figure 6 is a sectional view taken on line 6—6, Figure 5, and looking in the direction of the arrows.

Figure 7 is an enlarged fragmentary perspective view of the frame of the device.

Figure 8 is a sectional view taken on line 8—8, Figure 1, and looking in the direction of the arrows.

Figure 9 is a sectional view taken on line 9—9, Figure 8, and looking in the direction of the arrows.

Referring to the drawing in which the pre-

ferred embodiment of this invention is illustrated, 1 designates an ordinary plow beam and 2 a mold board. The colter device comprises a substantially V-shaped frame 3 upon the inner or lower end of which is pivotally mounted colter wheel 4. The V-shaped frame is curved upwardly at its outer end and its sides 5 are connected at their bottom edges by a runner bottom 6, Fig. 4. This bottom permits the frame to slide over corn stubble and weeds and the like, and should any dirt happen to fall between the sides 5 and onto the runner bottom 6, the same will readily pass out of the opening 7 and onto the ground.

The standard 8 extends through two parallel 15 webs 9 (Fig. 7) that are integral with the sides 5 of the V-shaped frame. These webs 9 have registering apertures 10 through which the lower end of the standard 8 extends. A horizontal slot 11 registers with the space between webs 9 and in 20 this space is placed collar 12; collar 12 fits around the standard 8 as clearly seen in Figures 5 and 6. The collar 12 is provided with an enlargement 13 and into this enlargement extends a set screw 14 which is adapted to impinge tightly against 25 the standard 8 (Fig. 6), thereby locking the frame 3 in an adjusted position upon the standard.

The slot 11 permits the frame 3 and wheel 4 to have a slight horizontal movement upon the standard, as indicated by the arrows A, Fig. 2, 30 whereby the life of the device is increased because of this yielding action in case the wheel strikes a large rock or considerable stubble, that might otherwise injure the device if it were not for the novel construction and movement, as just described.

A cotter pin 15 is placed in the lower end of the standard 8, and on the standard just above cotter pin 15 is a washer 16. This structure keeps the standard 8 from being accidentally pulled out 40 of the webs 9 and collar 12, but does not interfere with the operator's ready adjustment of the frame and its wheel to the desired position.

The standard 8 is mounted on beam 1 by passing 45 the standard through two loop bolts 17 (Figs. 8 and 9), with one of these loop bolts placed above and one below the plow beam 1. Suitable sleeves 18 are placed on these loop bolts in engagement with the plow beam 1, and on the sides of the plow beam 1 are strap irons 19 through 50 which the loop bolts extend. Suitable nuts 20 are on the outer ends of the loop bolts 17 in engagement with the outer strap iron 19, whereby the standard 8 is securely attached to the plow beam 1. Of course, it will be understood that the standard 8 fits tightly into the loops of bolts 17,

sufficiently to prevent any sliding movement of the standard upon beam 1 when in a fixed assembled position thereon.

From the foregoing description it is to be understood that I have provided a standard upon which is adjustably mounted a wheel-carrying frame, the adjustment being novel as well as the frame, whereby a highly efficient device is produced that will be a big help during plowing time, because it will slip over solid objects like rocks, stumps, etc., instead of breaking off the countershank.

To adjust the V-shaped frame upon the standard 8 all that is necessary is to unscrew or loosen set screw 14, whereupon the frame can be slid upward or downward upon the standard, and when the desired position is obtained, all the operator has to do is to tighten set screw 14 whereupon the adjustment is obtained.

It is to be understood that this colter device can be fastened to any ordinary plow and, further, the wheel 4 can be of any type that the operator desires.

The frame 3 is formed in a double curve; that is to say, the upper or outer half curves upwardly whereas the inner or lower half curves downwardly, or reversed curved in construction, as clearly shown in Figure 1. This construction places the colter wheel 4 in proper position for operation, with the runner or upper portion of the frame in proper position for contact with the stalks or weeds during the plowing operation.

While I have described the preferred embodiment of my invention and illustrated the same in the accompanying drawing, certain minor changes or alterations may appear to one skilled in the art to which this invention relates during the extensive manufacture of the same and I, therefore, reserve the right to make such alterations or changes as shall fairly fall within the scope of the appended claims.

What I claim is:

1. A colter, comprising a V-shaped wheel-carrying frame, including two upstanding sides, said sides at outer ends having a runner bottom integral with only their lower portions, said runner bottom having its inner end near the middle of said frame, a pair of transverse parallel webs entirely between the top and bottom edges of said upstanding sides and integral therewith, the lower web of said pair having one of its side edges contiguous to the inner end of said runner bottom, whereby an opening is formed between said lower web and the inner end of said runner bottom, one of said upstanding sides being provided with an elongated horizontal slot registering with the space between said parallel webs, a bodily movable collar between said webs and upstanding sides, said collar being provided with an enlargement extending through said elongated horizontal slot, a screw extending through said enlargement, a standard extending through said webs and collar, said screw engaging its inner end said standard, and a colter wheel on said frame.
2. A colter comprising a frame provided with upstanding sides, said frame also provided with a closed runner bottom at its outer end and with a colter wheel at its inner end, said upstanding sides provided near their middle and entirely within their marginal edges with two transversely positioned spaced webs, one of said upstanding sides provided with a longitudinally extending slot registering with the space between said webs, a collar between said webs and having a portion projecting through said slot, a standard extending through said collar, and means in the extended portion of said collar in the slot and gripping said standard for holding the standard in fixed relation with said collar.
